UNITED STATES PATENT OFFICE.

WILSON D. EDWARDS, OF TERRE HAUTE, INDIANA, ASSIGNOR TO TURNER GLASS COMPANY, OF TERRE HAUTE, INDIANA, A CORPORATION OF INDIANA.

DESIGN FOR A JUG.

Application filed July 30, 1927. Serial No. 22,955. Term of patent 7 years.

To all whom it may concern:

Be it known that I, WILSON D. EDWARDS, a citizen of the United States, residing at Terre Haute, in the county of Vigo and State of Indiana, have invented a new, original, and ornamental Design for a Jug, of which the following is a specification, reference being had to the accompanying drawing, forming part thereof.

The figure is a side elevation of a jug showing my new design.

I claim:

The ornamental design for a jug as shown.

WILSON D. EDWARDS.
